UNITED STATES PATENT OFFICE.

JOHN KERR, OF TORONTO, ONTARIO, CANADA.

AIR COMPRESSOR.

Application filed July 9, 1920. Serial No. 395,016.

To all whom it may concern:

Be it known that I, JOHN KERR, a subject of the King of Great Britain, and resident of 122 St. Patrick St., in the city of 5 Toronto, in the county of York, in the Province of Ontario, in the Dominion of Canada, have invented certain new and useful Improvements in Air Compressors, of which the following is a specification.

10 The invention relates to improvements in air compressors as described in the present specification and shown in the accompanying drawings that form a part of the same.

The objects of the invention are to permit 15 of the compression of air to a greater degree than has hitherto been possible, to simplify the mechanism necessary for such purpose and generally to provide an air compressor which will be inexpensive to construct, simple of operation, efficient and durable.

In the drawings Figure 1 is a plan view of the device with the head or cap of the compression chamber removed.

20 Figure 2 is a side elevation of the device, a portion of the gearing being broken away to disclose parts therebehind.

Figure 3 is an end view of Figure 2, with the lower portion of the tank broken away.

Figure 4 is a sectional view taken substantially on the line A—A of Figure 7.

Figure 5 is a sectional view through Figure 4 taken on the line B—B.

35 Figure 6 is a plan view showing portions of the chambers adapted to contain the sealing discs.

Figure 7 is a vertical sectional view taken on the line C—C of Figure 3.

40 Figure 8 is a cross sectional view taken on the line D—D of Figure 3.

Figure 9 is a detail of the spring used in the construction of the worm or screw employed to force the air into the tank.

45 Figure 10 is a plan view of one of the sealing discs.

Figure 11 is an edge view of the disc shown in Figure 10.

50 Figure 12 is a horizontal sectional view taken on the line D—D of Figure 7.

Like numerals of reference indicate corresponding parts in the various figures.

Referring to the drawings 1 is a stand constructed to accommodate the various 55 parts of the apparatus and which may be located in any desired position but is pref-

erably supported above the air tank 2 and spaced therefrom.

3 are brackets supported in parallel vertical arrangement by the stand 1 and having 60 openings therethrough forming bearings for a shaft 4 rotatable therein.

5 is a gear wheel rigidly mounted on the shaft 4 and being adapted to be connected in any desired manner with the source of 65 power, (not shown in the drawings) said wheel being provided on one side thereof with a comparatively small bevel gear 7.

8 are eccentrics rigidly mounted on opposite ends of the shaft 4 and having pivoted 70 thereto piston arms 9 controlling pistons operating in air cylinders 10, said cylinders being supported in horizontal arrangement by any desired means although shown in the drawings as supported by uprights 11 bolted 75 to the stand 1.

12 are air inlet tubes projecting from the ends of the air cylinders and containing valves 12^a adapted to permit of air entering the cylinders upon the suction stroke of 80 the pistons and automatically closing upon the compression stroke of said piston. (The construction of these valves is not shown in the drawings as there are many well known forms of valves which may be used.) 85

13 is the lower section of the casing adapted to contain the compression screw or worm and the sealing discs, said section comprising a central portion 14 substantially semi-circular in cross section and being considerably greater in length than the cylinders 10, and comparatively shallow opposing compartments 15 located on opposite sides of the said central section, said compartments being preferably substantially circular in horizontal section and being provided with circular runways 16 leading to the central or screw compartment 14.

The central portion 17 of the compartments 15 may be formed integral with the section 13 or may be in the form of discs secured to said section, as shown in the drawings, and are cut away straight as at 18 to extend parallel with the edge of the screw compartment 14.

If desirable the bases of the runways 16 may be grooved as at 19 or otherwise constructed to form trackways, thus serving to reduce friction and facilitate the movement of the sealing discs therealong.

21 is a worm gear operating in the end 110 of the chamber 14 adjacent to the drive

mechanism, said gear being mounted on a shaft 22 enlarged at one end and journaled in the front wall of the compartment 14 and at its other end extending through the corresponding wall of said compartment and carrying a gear 23 thereon.

24 is a shaft rotatably journaled in a horizontal position by bearings in a bracket 25 from the stand 1 and carrying at one end 10 a bevel gear 25^a meshing with the bevel gear 7 extending from the wheel 5 and at its other end carrying a gear wheel 25^b meshing with the gear 23 so that motion imparted to the wheel 5 will be transmitted 15 to the worm gear 21.

26 is a substantially circular block or partition inserted in the central compartment at the forward end of the worm 21 and in the path of the sealing discs and being provided with openings 27 there-through located below the plane of the floors of the compartments 15 to permit of the air being forced by the screw 21 into the forward end or chamber 28 formed by 25 the insertion of said partition.

The partition 26 is slotted on opposite sides as at 29 to permit of the passage of the sealing discs so as to eliminate the possibility of escape of air in passage from 30 one compartment to the other.

The edges or threads 30 of the screw 21 are hollowed out slightly forming a comparatively shallow air chamber around the screw, adapted to be covered by a resilient 35 strip 31 of material secured at its ends to the screw and being otherwise free to vibrate upon the rotation of said screw so that any backward rush of air will force itself beneath said strip and raise said strip into 40 engagement with the wall of the chamber and effectually prevent any possibility of air escaping.

32 are the sealing discs adapted to be inserted in the runways 16 and to be operated 45 therearound through the rotation of the screw 21 said discs being of sufficient diameter to tightly engage one another and the opposite sides of the runway and being 50 closely the contour of the concave portions of the screw 21 so that it is absolutely impossible for any air to escape from the forward part of the central compartment 14.

It is preferable that the edges of the 55 discs 32 be covered with a band 33 of rubber or other resilient material so that when the various discs are forced tightly together positively air tight joints will be formed.

34 is a tank located below the casing 13 60 and receiving the air from the cylinders 10 through pipes 35 leading from the forward ends of said cylinders to the corresponding end of the tank, said tank being provided with an opening through the top 65 thereof registering with a slot 36 through

the bottom of the compartment 14 so that in operation the air which is forced from the cylinders 10 will enter the tank 34 under compression and will be forced through the opening 36 into the said compartment 70 14 from which it will be forced by the revolving screw through the openings 27 into the compartment 28.

37 is a tube communicating with the forward end of the casing 13 through an opening 38 in the bottom of said casing and entering the tank 2 at any desired point. 75

In the operation of this invention the motor or other power mechanism is set in motion causing the rotation of the wheel 5 80 and consequently the shaft 4 and eccentrics 8 and as said eccentrics are rotated the piston arms 9 are reciprocated causing the pistons to be operated within the cylinders 10. 85

Upon each suction stroke of the pistons 85 air is drawn into the cylinders through the tubes 12 and upon the reverse stroke the air is forced through the tubes 35 into the tank 34 and through the opening 36 in the top thereof into the compartment 14 and by 90 means of the screw 21, which is rotated through the connection of the various gears, it is forced forwardly and compressed to a very high degree and forced through the openings 27 into the compartment 28 and 95 thence through the comparatively small tube 37 into the tank 2.

As the slot 36 through which the air enters the compartment 14 is located in advance of the rearmost point at which the 100 screw engages the discs no air can possibly escape rearwardly and as the screw 21 in its operation firmly engages the discs 32 and carries them forwardly the air in said compartment can only flow in a forward direction and through the openings 27. 105

What I claim is:—

1. In an air compressor, a receiving tank, a piston and cylinder having an air inlet and suitable check valve, an intermediate 110 chamber communicating with said receiving tank, a screw drive suitably enclosed and communicating with said intermediate chamber and with said cylinder and means for operating said piston and said screw 115 drive coincidently to drive the air continuously to the receiving tank in superpressed quantities.

2. In an air compressor, a cylinder having an air inlet and check valve and a piston 120 operating therein, a spiral driving member suitably mounted, means for driving said piston and said spiral member coincidently, a casing containing said spiral member and having contiguous chambers and connected with said cylinder, rotatable discs constituting packing members engaging 125 said spiral member and enclosed in certain of said contiguous chambers and a receiving tank connected with a chamber con- 130

tiguous to the chamber containing said spiral driving member.

3. In an air compressor, a cylinder having an inlet and check valve and a piston operating therein, an intermediate chamber communicating with said cylinder and receiving the air therefrom, a screw drive suitably enclosed and receiving the air from said intermediate chamber and delivering said air to said tank in superpressed quantities, means for driving said piston and said screw drive coincidently and means operable coincidently with said screw drive for preventing back flow of air.

15 4. In an air compressor, a cylinder having an inlet and check valve and a piston operating therein, an intermediate chamber communicating with said cylinder and receiving air therefrom, a worm gear, a casing having a central worm chamber receiving air from said intermediate chamber and contiguous chambers forming enclosures for packing discs engaging said worm gear and operable thereby, a tank receiving the air from said intermediate chamber through the operation of said worm gear and means for driving said piston and said worm gear coincidently.

5. In an air compressor, a receiving tank, an intermediate air chamber, cylinders having air inlets and check valves and pistons operating in said cylinders respectively and forcing the air into said intermediate chamber, a screw drive, a casing having a central compartment containing said screw drive and contiguous chambers on opposite sides thereof constituting runways communicating with said central compartment, rotatable packing discs operable in said runways through engagement with said screw drive and forming therewith means for forcing said air into said receiving tank in superpressed quantities, and means for driving said pistons and said screw drive coincidently.

6. In an air compressor, a receiving tank, an intermediate air chamber, cylinders having air inlets and check valves and pistons operating in said cylinders respectively and forcing the air into said intermediate chamber, a screw drive, a casing having a central compartment containing said screw drive and oppositely disposed contiguous chambers constituting substantially circular runways leading to said central compartment, packing discs operable in said runways respectively through engagement with said screw drive and forming therewith means for forcing said air into said receiving tank in superpressed quantities, said casing being provided intermediately thereof with a partition having air outlets leading to said receiving tank and being slotted to receive said discs in passage and means for driving said pistons and said screw drive coincidently.

7. In an air compressor, a receiving tank, cylinders having pistons operating therein and air inlet valves, an intermediate air chamber communicating with said cylinders and having an air outlet, a gear casing communicating with said intermediate chamber through said outlet and receiving the air therefrom and having oppositely disposed contiguous chambers of comparatively shallow design and provided with substantially circular runways leading to said gear casing, a spiral gear journaled in said casing and adapted to advance the air from said intermediate chamber to said receiving tank, sealing discs carried by said runways and movable through engagement with said gear, said discs being provided with flexible bands circumferentially arranged thereon, and mechanism adapted to operate said pistons and said spiral gear coincidently.

8. In an air compressor, a receiving tank, cylinders having pistons operating therein and air inlet valves, an intermediate air chamber communicating with said cylinders and having an air outlet, a gear casing communicating with said intermediate chamber through said outlet and receiving the air therefrom and having oppositely disposed contiguous chambers provided with substantially circular runways leading to said gear casing, a spiral gear journaled in said casing and adapted to advance the air from said intermediate chamber to said receiving tank, said gear being provided with means adapted to seal said casing against the escape of air, sealing discs carried by said runways and movable through engagement with said gear, and mechanism adapted to operate said pistons and said spiral gear coincidently.

9. In an air compressor, a receiving tank, cylinders having pistons operating therein and air inlet valves, an intermediate air chamber communicating with said cylinders and having an air outlet, a gear casing communicating with said intermediate chamber through said outlet and receiving the air therefrom and having oppositely disposed contiguous chambers provided with substantially circular runways leading to said gear casing, a spiral gear journaled in said casing and adapted to advance the air from said intermediate chamber to said receiving tank, the threads of said gear being hollowed and provided with a resilient covering, sealing discs carried by said runways and movable through engagement with said gear, and suitable gear mechanism adapted to operate said pistons and said spiral gear coincidently.

Signed at the city of Toronto, this 20th day of May, 1920.

JOHN KERR.
